UNITED STATES PATENT OFFICE.

PETER A. MANDABACH, OF COLUMBUS, OHIO.

DESIGN FOR A BADGE.

No. 38,844.

Specification for Design.

Patented Oct. 8, 1907.

Application filed July 16, 1907. Serial No. 384,114. Term of patent 3½ years.

To all whom it may concern:

Be it known that I, PETER A. MANDABACH, a citizen of the United States, residing at Columbus, in the county of Franklin and State of Ohio, have invented a new, original, and ornamental Design for Badges, of which the following is a specification, reference being had to the accompanying drawing, forming part hereof.

The figure is a face view of a badge, showing my design.

I claim:

The ornamental design for a badge as shown.

PETER A. MANDABACH.

Witnesses:

B. MANDABACH,
M. F. SPENCER.
